UNITED STATES PATENT OFFICE.

CLAUDE DE F. SMITH, OF PORTLAND, OREGON, ASSIGNOR TO SMITH SIGNAL CORPORATION, OF NEW YORK, N. Y., A CORPORATION OF DELAWARE.

LAMP BOX.

1,402,100.

Specification of Letters Patent.

Patented Jan. 3, 1922.

Application filed November 30, 1915. Serial No. 64,289.

To all whom it may concern:

Be it known that I, CLAUDE DE F. SMITH, a citizen of the United States, residing at Portland, in the county of Multnomah and 5 State of Oregon, have invented certain new and useful Improvements in Lamp Boxes; and I do hereby declare the following to be a full, clear, and exact description of the invention, such as will enable others skilled in 10 the art to which it appertains to make and use the same.

This invention relates to illuminated signs, and more especially to lamp boxes having perforated faces; and the object of the same 15 is to produce a simple and convenient signal box for automobiles and the like which is practically inaccessible to dirt and yet wherein the parts can be readily disconnect- 20 ed to replace or repair a bulb.

Another and important object of my pres- 25 ent invention is to provide for the giving of signals from a moving vehicle in city thor- 30oughfares or other roadways so that similar signals or signals may be transmitted simulta- 35 neously and effectually from a point on the vehicle, the disposition of the signal being such that it may be readily viewed from al- 40 most any point in the front of the vehicle and through a large range of vision from the rear of the vehicle. In the accomplishment 45 of this object of my invention I provide a signal lamp which consists of front and rear signal means each provided with a series of indicia or sign words, the front and rear sign means being duplicate, and the sign words 50 or signal media being arranged on opposite sides of the lantern so as to provide for the illumination at the front and rear of the given indicia to cause similar signs to be dis- 55 played and to provide for the selective illu- 60 mination of any one of the set of duplicate signs. While my present invention contem- 65 plates a traffic signal it is particularly adapt- 70 able for use upon automobiles or other ve- 75 hicles, and when mounted upon the left hand side of the body of the vehicle in a plane somewhat above the mud guards of the same and preferably located toward the rear left 80 corner of the vehicle body my sign is espe- 85 cially capable of being read through a large 90 range of view from the front, left side, and the rear.

A further object of the invention is to provide for the efficient display of signs

through means normally dormant and adapt- 55 ed to be selectively illuminated, the said means consisting of transparent or translu- 60 cent media between which there is prefer- 65 ably disposed a barrier to prevent the pas- 70 sage or transmission of light from one side of the lamp to the other, and this eliminates possible confusion of the signs by reason of the transmission of rays from one side to the other.

The invention consists broadly in two tele- 65 scopic members, the outer being attached to the supporting means and the inner having cells in which are disposed electric lights or 70 bulbs, and the stenciled side plates and glass panels are removably held between these members when the latter are assembled. Details are set forth below and shown in the drawings wherein:

Figure 1 is a side elevation of this lamp partly broken away and with one corner in 75 section.

Figure 2 is a vertical section on the line 2-2 of Figure 1 with the two members slightly moved from their assembled position.

Figure 3 is a perspective detail of the outer member or casing.

Figure 4 is a perspective detail of the inner member.

The outer member of this lamp box which 85 may well be called the casing, is by prefer- 90 ence made of sheet metal suitably treated to prevent rust, and comprises a top 1 from whose extremities depend integral end pan- 95 el 2, each having a pair of holes 3 near its lower end, and flanges 4 and 5 extend around the edges of these three panels and the lower extremities of the end flanges are preferably beveled as at 6. The support is herein shown as a short section of pipe 7 connected with a 95 floor plate 8 which is screwed or riveted as at 9 to the top panel 1, and the upper end of the pipe may be attached in any suitable manner to an overhead element such as the fender, or may in fact be bent at an angle 100 and attached to the side of an automobile body.

The inner member is divided by partitions as explained below so as to produce cells, and may well therefore be called the cellular 105 member. It also is by preference made of sheet metal, and comprises a top panel 11, two end panels or walls 12, and a bottom

panel or wall 13 which, as seen in Figure 2, may be of double thickness with the side edges of the two thicknesses turned up into inner and outer flanges 14 and 15. Horizontal partitions 16 connect the end walls 12, and two of these partitions are herein shown which will produce three compartments or cells 17. By preference a vertical wall or partition 18 also connects the end walls and 10 crosses the horizontal partitions at their centers so as to sub-divide the cells as shown. Where these several walls and partitions intersect, they may be connected in any suitable manner, and the side edges of the top 15 11 and the two horizontal partitions may be bent into flanges 19 if desired. The width of these horizontal parts is the same as that of the inner or upper bottom wall, and this is slightly less than the distance between the 20 inner faces of the two flanges 5, 5; whereas the width of the outer bottom wall is the same as the width of one end panel of the outer casing, and its flanges 15 stand in the same plane as the flanges 5 and are by preference beveled at their extremities as shown 25 at 6'.

I do not wish to be limited to the illuminating means, but as probably the most modern and convenient I preferably employ 30 electric bulbs T removably engaged with sockets S which are bolted as seen at B to opposite sides of the upright partition 18, and wires W lead from the various bulbs to an insulating nipple N in the bottom of the 35 inner member, and thence through a source of electricity and a switch within reach of the driver, these latter features being well-known and not necessary to illustrate.

Between the two members of the lamp 40 box thus described, and at each side thereof, is mounted a metal plate 20 having words stenciled through it as shown at 21 in Figure 1, and outside the plate a sheet of glass 22, the lower ends of these two elements resting in the channel between the flanges 14 and 15, the plate resting against the ends of the horizontal partitions 16 (or their flanges 19 if the latter are employed) and the glass overlying the plate and its 45 edges standing behind the flanges 5 and 15. To assemble the parts of this lamp box the stencil plates and glasses are laid against both sides of the cellular member with their lower edges between its flanges, their upper 50 edges are borne inward against the edges of the top 11 and held in one hand, and the outer casing is held in the other hand if, indeed, it be not sufficiently supported from overhead as at 7. The upper end of the inner member is then passed into the lower end of the outer member, and the inner member slid or pushed bodily inward, carrying the stencil plates and glasses with it as will be seen from Figure 2, until the 55 parts reach the position shown in Figure 1, at which time the beveled ends 6' of the flanges 15 will come into close contact with the beveled ends 6 of the flanges 5. Screws 3' are now passed inward through the holes 3 and into other holes 12' in the end walls 70 12 of the inner member; and if the metal of the latter be rather thin these holes may be surrounded by bosses 13' or the metal otherwise made thicker at this point as seen in Figure 2. The screws connect the two 75 members and hold them in this position, and the wires W lead through the nipple N and out the bottom of the lamp box. To gain access to the interior, as for replacing a burned out bulb, the screws are withdrawn 80 and the inner member slid downward from within the outer member. As soon as the glass plates and stencils have been disengaged from the lower ends of the flanges 5 of the outer member, they fall or can be 85 taken out of place and the operator gains immediate access to the cells 17. Also I have shown the stencils as solid plates with openings for the letters forming the words, and the glass panels as overlying the stencils 90 whereby the color of the glass is shown through the letters; but in these respects I reserve the broadest rights possible. The matter of the wiring forms no part of the present invention, but by preference I lead 95 the wires through the bottom of the removable member so that when this member is taken out of the fixed member the flexibility of the wires is useful in a manner which will be clear. The words Left, Right and Stop 100 indicated herewith are those most useful when the lamp box is employed as an automobile signal, and I would not be limited in this respect. Finally, while I prefer that the support shall be connected with the 105 outer member, it need not be attached to the top panel thereof and its shape and details of construction are unimportant.

What I claim is:

1. In a lamp box, the combination with an 110 outer substantially U-shaped member having closed top and end panels with flanges around their edges; of an inner member of a size to fit telescopically within the outer member, inner and outer flanges along the 115 side edges of its bottom, the outer flanges alining with the flanges on the outer member, lighting means within the inner member, and sign plates removably held between the inner and outer members and inside the flanges of the latter and between the flanges on said bottom. 120

2. In a lamp box, the combination with an 125 outer member having closed top and end panels with flanges around their edges; of an inner member having bottom and end panels and of a size to fit telescopically within the outer member, flanges along the edges of its bottom, lighting means within the inner member, plates removably held 130

- between the inner and outer members and inside said flanges of the latter and provided with illuminated signs, and detachable fastening means between the end panels 5 of said members.
3. In a lamp box, the combination with an outer member having top and end panels with flanges around their edges; of an inner member having top, bottom, and end panels 10 and of a size to fit telescopically within the outer member, said top and bottom having flanges along their side edges, electric lighting means within the inner member, wires leading therefrom through the bottom of 15 this member, sign plates removably held between said flanges of the outer and inner members, and detachable fastening means passing through the ends of the outer member and into the ends of the inner member.
- 20 4. In a lamp box, the combination with an outer member having top and end panels and flanges along their edges; of an inner member telescopically insertable into the outer member and including top and bottom 25 panels and end walls, a divisional panel connecting said walls and of the same width as said top and bottom panels, sign plates removably held between the flanges and the edges of said top, bottom, and divisional 30 panels, and detachable fastening means between the two members.
5. In a lamp box, the combination with an outer member having top and end panels and flanges along the side edges of the latter, 35 and a support for this member; of an inner member telescopically insertable into the outer member from below and including top and bottom panels and end walls, and horizontal partitions connecting said walls 40 and of the same width as said top and bottom panels, the partitions producing cells, illuminating means within said cells, a flexible conveyer for the illuminant fluid passing through said bottom to such means, plates 45 removably held between the flanges and the edges of said top, bottom, and partitions, and detachable fastening means between the two members.
6. In a lamp box, the combination with an 50 outer member having top and end panels and flanges along the side edges of the latter, and a support for this member, of an inner member telescopically insertable into the outer member from below and including top 55 and bottom panels and end walls, and horizontal partitions connecting said walls and of the same width as said top and bottom panels, the partitions producing cells, illuminating means within said cells, detachable fastening means for holding said inner and outer members when assembled, and at each side of the lamp box a stencil plate 60 and overlying it a glass plate both held inside said flanges and against the edges of 65 said partitions.
7. In a lamp box, the combination with a substantially U-shaped outer member having its sides and bottom open, and a support for this member, of stencil plates removably closing the open sides of such member, an inner member removably insertable into the bottom of the open member and between said plates, horizontal partitions within this member whose edges lie inside said plates and which partitions divide the member into 70 cells, an upright partition within this member crossing said horizontal partitions and sub-dividing said cells, detachable means for holding these members when assembled, and an illuminating device in each subdivision of the cells.
8. In an automobile signal, the combination with a substantially U-shaped outer member having its sides and bottom open, and a support for this member; of stencil plates removably closing the open sides of such member, an inner member removably insertable into the bottom of the open member and between said plates, horizontal partitions within this member whose edges lie 75 inside said plates and which partitions divide the member into cells, an upright partition within this member crossing said horizontal partitions and sub-dividing said cells, detachable means for holding these 80 members when assembled, and an illuminating device in each subdivision of the cells adapted to show to the front and to the rear, whereby, when the signal is attached to the rear left hand side of an automobile, a spectator can read the signal from the rear or from the front of the automobile.
9. A signal lamp having a casing structure open at opposite faces and at the bottom, a box telescopically fitting the casing and also open at opposite sides corresponding to the casing-openings, sign-forming members carried by the box and covering the open sides thereof, said members having 90 duplicate series of separate signs, a series of pairs of lamps mounted in the box, one pair of lamps for each pair of similar signs, partitions dividing the box into front and rear chambers, and shelves subdividing the 95 chambers into a series of parallel compartments one for each sign.
10. In an automobile signal the combination with an outer casing member having its sides and bottom open, the sides having flanges, of an inner structure removably insertable into the bottom of the outer member, sign plates interposed between the flanges of the open sides of said member and said structure, horizontal partitions in 105 this structure whose outer edges lie between said sign plates and which partitions divide the structure into cells, upright means partitioning and subdividing said cells, means for detachably holding said member and 110
- 115
- 120
- 125
- 130

structure assembled, and an illuminating device in each subdivision of the cells adapted to show to the front and to the rear, whereby, when the signal is attached to the rear left hand side of an automobile, a spectator can read the signal from the rear or from the front of the automobile.

In testimony whereof I affix my signature in presence of two witnesses.

CLAUDE DE F. SMITH.
